UNITED STATES PATENT OFFICE.

FREDRIK LJUNGSTRÖM, OF LIDINGO-BREVIK, SWEDEN, ASSIGNOR TO AKTIEBOLAGET LJUNGSTRÖM ANGTURBIN, OF LIDINGO-BREVIK, SWEDEN, A CORPORATION.

AIR-COOLED CONDENSER FOR LOCOMOTIVES OR SIMILAR VEHICLES.

Application filed January 28, 1925. Serial No. 5,386.

To all whom it may concern:

Be it known that I, FREDRIK LJUNGSTRÖM, a subject of the King of Sweden, residing at Lidingo-Brevik, Sweden, have invented certain new and useful Improvements in Air-Cooled Condensers for Locomotives or Similar Vehicles, of which the following is a specification.

Condensers for locomotives or similar vehicles are known which consist of a part comprising condenser tubes or pipes, said part being cooled by air forced over it by means of fans, and adapted to co-operate with a liquid container, either in such a manner that steam is caused to pass through the condenser tubes, the said container then serving as a sort of storer, or, in such a manner that the steam is first condensed in a separate condenser of any type while the cooling liquid for this condenser is caused to pass through the air-cooled part which thus acts as a recycler for the cooling liquid which, some way or other, has absorbed the heat of the steam. In both cases the condenser tubes have been disposed above the liquid container or at least above the plane formed by the surface of the liquid therein. This arrangement of the condenser tubes has been necessitated for the reason that it has always been a desideratum that the liquid contained in the condenser tubes or in the condenser elements should by itself flow back into the container. This, obviously, is an indispensable condition where steam is condensed in the elements, as water of condensation then formed fills up the lower portion of the elements, thus rendering the utilization of the whole element for condensation purposes impossible, but in cases, too, where the air-cooled part serves as a means for recooling the cooling liquid, it is desirable that the cooling liquid may flow back automatically, especially when the locomotive is standing still, inasmuch as it will then be possible to replace or to repair the condenser tubes or elements, without incurring the necessity of first drawing off liquid from the condenser. If liquid is allowed to remain in the lower portions of the condenser tubes the risk is also incurred that the said tubes will freeze and burst when the outer temperature is low.

In order to render possible that the liquid

in the lower portions of the elements may by itself flow back into the container in cases where steam is caused to pass through the elements, it is not only necessary, however, that the elements be arranged above the plane formed by the level of the liquid in the container; a certain suction height must also be provided in order to overcome the vacuum in the elements which is always greater than that in the container.

However, by the disposition of the condenser tubes or elements in this manner, that is to say, at a certain level above the level of the water in the liquid container, the point of gravity of the condenser will be disposed relatively high. Moreover, in such a construction, the space available as limited by the loading gauge cannot be fully utilized, which evidently is a desideratum, for the purpose of obtaining a condenser with a capacity as large as possible per unit of length. This is particularly the case with the space within the lower portion of the loading gauge.

The present invention relates to an arrangement in condensers adapted for locomotives or similar vehicles, such condensers consisting of condenser tubes or elements adapted to be cooled by air, and of a liquid container adapted to co-operate therewith, the lowermost portions of the condenser tubes being located below the plane determined by the water level in the container, by which arrangement, the point of gravity of the condenser will be situated further down, and the lower space within the loading gauge will be better utilized. The invention consists in that the condenser tubes or elements are connected with a collecting well which is under vacuum and disposed at a lower level than the tubes or elements and the liquid container, to which collecting well the liquid coming from the condenser elements flows and from which it may be conveyed by means of a pump to the liquid container.

The invention is disclosed in the accompanying drawings. Fig. 1 is an elevation of a locomotive provided with a condenser according to the invention. Fig. 2 shows a section through a somewhat modified embodiment of the condenser vehicle pertaining to the said locomotive.

According to Fig. 1, 1 and 2 designate two

vehicles which together form the locomotive, and of which vehicles the one denoted by 1 carries the boiler and the driver's cab of the locomotive, while the vehicle 2 carries the condenser 4 and the driving means 3 of the locomotive. In the embodiment shown, the driving means consists of a steam turbine from which the motion is transmitted to the driving wheels 5 by means of a toothed gearing disposed in the casing 6, as well as through the medium of cranks and coupling rods 7.

In the embodiment shown, the condenser consists of a liquid container 8, serving as a steam storer operating under vacuum, and of condenser tubes or elements 9 disposed on either side thereof (see Fig. 2). 10 designates fans which are so arranged that they suck the air required for the cooling through the elements in the direction of the arrow 11, that is to say, substantially in a direction from below and obliquely upwards. Steam from the main machinery of the locomotive, or, perhaps, from some existing auxiliary machinery, enters the container above the level of the liquid B—B, where the same is either condensed directly by the water sprinkling down from a diaphragm 12, or is caused to flow through the pipes 13 to and through the elements 9 of the air-cooled part. The action is as just described for the reason that the container, as already set forth, acts as a storer, in that the same will, in periods when the engine gives off a large quantity of steam, accumulate a portion of this steam, and then, when the engine gives off a smaller quantity of exhaust steam, will deliver steam to the air-cooled portion.

The condenser tubes or elements are in known manner inserted in groups, at the bottom, into common collecting chambers 14 communicating with collecting pipes 15 extending in the longitudinal direction of the condenser.

According to the invention, these collecting pipes 15 are connected to a collecting well 16 disposed underneath the said pipes and under the liquid container 8, the water forming in the lower portion 17 of the elements 9, in the collecting chambers 14 and in the collecting pipes 15 being thus caused to flow by itself into the said collecting well. If such collecting well were not present, but the elements were connected to the container directly, obviously the portions 17 of the elements 9 or the collecting chambers 14 and the collecting pipes 15 situated underneath the line B—B indicating the level of the liquid would always stand full of water.

The water collected in the collecting well 16 is pumped by means of a pump 18 driven from one of the shafts of the fans and consisting in the embodiment shown of a propeller pump, onto the top side of the diaphragm 12 from where the water, as previ-

ously mentioned, sprinkles down through the container 8. The capacity of the pump is such that it will be able to convey a larger quantity of water than will normally flow down from the elements 9, so that the water in the collecting well 16 is not allowed to rise above a certain level, whereby a height of fall 19 of a certain minimum for the water from the elements to the well is always maintained. In order that the pump 18 shall not entirely empty the collecting well, and in order that the pump shall always have water for feeding purposes or for circulation in the container, there is provided a float valve 21 in the well 16, which float valve opens the communication to the container 8 situated thereabove, when the level of the liquid in the well has sunk down to a certain minimum value. Water will then flow down from the container 8 through the pipe 22 into the well 16, it being thus ensured that the pump 18 has always water in the suction pipe.

According to the invention, the elements may, obviously, be made longer, than would otherwise be possible, in that the same could not, if no collecting well 16 were present, be extended further down than that their lowermost parts would be situated above the level B—B of the liquid in the container. If it is not essential to make the elements longer, another advantage is attained according to the invention, consisting in that the whole condenser may be made lower. As will be seen from Fig. 1, an unobstructed view will thus be had rearwards from the driver's cab over the condenser, in that a window in the rear wall of the driver's cab above the highest level of the condenser, as indicated by the line 20, provides an unobstructed view for the driver rearwards over the track, for instance, when running backwards, which in many countries is an indispensable condition for locomotives.

Evidently, a plurality of collecting wells 110 may be provided for the elements 9, for example, a collecting well for each separate portion of the air-cooled part. Preferably, however, a collecting well is provided which is common to all of the portions of the air-cooled part.

In the embodiment shown, only the lower portions 17 of the elements 9 are situated below the level B—B of the liquid in the container, but the entire air-cooled part may also be conceived as placed underneath this level. Such a condenser construction may be conceived as being used in cases where particularly large liquid containers are required (for instance on tracks with great and long gradients requiring an increased accumulating capacity of the container), and when the loading gauge required by the laws is very wide at the bottom.

What I claim as new and desire to secure

by Letters Patent of United States of America is:—

1. A condenser for locomotives and similar vehicles, comprising a liquid container, condenser elements co-operating with said container, the lowermost portions of said elements being located adjacent to or below the bottom of the container, a collecting well situated at a lower level than said elements and said container, means to connect said elements with said collecting well and means consisting of a pump to convey to said liquid container the liquid flowing down from said elements into said collecting well.
- 15 2. A condenser for locomotives and similar vehicles, comprising a liquid container, condenser elements co-operating with said container and arranged on opposite sides of same, the lowermost portions of said elements being located adjacent to or below the bottom of the container, a collecting pipe common to the elements on each side of said container, a collecting well disposed at a lower level than said collecting pipes and

said container, means to connect said elements with said collecting well and means consisting of a pump to convey to said liquid container the liquid flowing down from said elements into said collecting well. 25

3. A condenser for locomotives and similar vehicles, comprising a liquid container, condenser elements co-operating with said container, the lowermost portions of said elements being located adjacent to or below the bottom of the container, a collecting well situated at a lower level than said elements and said container, means to connect said elements with said collecting well, means consisting of a pump to convey to said liquid container the liquid flowing down from said elements into said collecting well, and means consisting of a float valve in said collecting well to permit liquid to pass down from said container into said collecting well, when the quantity of liquid in said collecting well falls below a certain value. 30 35 40 45

In testimony whereof I affix my signature.

FREDRIK LJUNGSTRÖM.
